UNITED STATES PATENT OFFICE.

TRUMAN McCORD AND WILLIAM C. BIGLER, OF REW, PENNSYLVANIA.

WELL-DRILLING MACHINE.

1,010,507.

Specification of Letters Patent.

Patented Dec. 5, 1911.

Application filed October 15, 1910. Serial No. 587,339.

To all whom it may concern:

Be it known that we, TRUMAN McCORD and WILLIAM C. BIGLER, citizens of the United States, residing at Rew, in the 5 county of McKean and State of Pennsylvania, have invented certain new and useful Improvements in Well-Drilling Machines, of which the following is a specification, reference being had to the accompanying 10 drawings.

This invention relates to improvements in pumping or drilling machines and has for its object to provide an improved support for an operating shaft including hollow metallic jack posts and means for rigidly 15 mounting said posts upon a mud sill and for securing the shaft upon the upper end thereof.

A further object of the invention is to 20 provide a very simple and easily arranged supporting structure for a crank shaft and one which is light and extremely rigid.

Another object is to provide spaced tubular jack posts arranged in bearings upon a 25 mud sill, bearing caps for a crank shaft arranged upon the upper end of the posts, and vertical tie rods extending through said posts, the mud sill and said caps to rigidly 30 secure the crank shaft upon the upper ends of the posts.

With these and other objects in view, the invention consists of the novel features of construction, combination and arrangement 35 of parts hereinafter fully described and claimed, and illustrated in the accompanying drawings, in which—

Figure 1 is a side elevation illustrating the arrangement of my improved jack posts; Fig. 2 is a vertical longitudinal section; Fig. 3 is a section taken on the line 40 3—3 of Fig. 2; and Fig. 4 is a top plan view.

Referring more particularly to the drawing 5 designates the mud sill which is adapted to be arranged below the surface of the ground as shown in Fig. 1. Bearing plates 6 are arranged upon the mud sill 5 and are formed with flanges 6' to provide an extended bearing surface. These bearing 45 plates are formed with annular flanges 6" to receive the lower ends of the jack posts 7. These posts are of hollow metallic construction and are of sufficient length to extend the desired distance above the ground 55 surface. The posts 7 are rigidly connected intermediate of their ends or at about the

ground level, by means of a bolt 8 which extends through the posts and has a nut 9 threaded on each end thereof.

Upon the upper ends of the jack posts 7 bearing caps 9^a are arranged, said caps having rotatably mounted in the bearing portions 9' thereof, a crank shaft 10 which is adapted to be connected to the walking beam of a drill or pump in the usual manner. Upon one end of the crank shaft a band wheel 11 is secured over which a suitable driving belt passes and extends to the motor or other source of power. The bearing caps 9 are rigidly held upon the upper 70 ends of the sill posts 7 by means of the tie rods 12 which extend vertically therethrough. The upper ends of these rods extend through the caps 9 and the lower ends thereof extend through openings in the mud 75 sill 5. Upon the ends of said rods the nuts 13 are threaded whereby all of the parts are rigidly clamped together, said tie rods holding the posts 7 in the bearing plates 6 and the caps 9 upon the upper ends of said 80 posts. As shown in Fig. 3 two of the tie rods extend through each of the posts 7 and are arranged upon opposite sides of the crank shaft 10, said shaft being centrally mounted upon the bearing caps 9. Thus 85 there is an equal pressure of the caps 9 upon all points of the upper end of the hollow posts thereby obviating the liability of weakening the structure.

From the foregoing it will be seen that 90 we have devised a very simple shaft supporting structure for drilling or pumping machines which is light and comparatively inexpensive to manufacture. The posts may be easily and quickly arranged in position 95 and by means of the connecting bolt 8 and the tie rods 12 it will be obvious that an extremely rigid structure is provided.

While we have shown and described the preferred embodiment of our invention, it 100 will be understood that the device is susceptible of considerable modification without departing from the essential feature or sacrificing any of the advantages thereof.

Having thus described the invention what 105 is claimed is:—

In a machine of the character described, the combination of a mud sill, spaced bearings arranged upon said sill, hollow metallic posts mounted in said bearings at their 110 lower ends, bearing caps removably arranged upon the upper ends of said posts

to support a crank shaft thereon, a pair of spaced tie rods vertically disposed through each of said posts and extending at their upper ends through said bearing caps 5 on opposite sides of the crank shaft, the lower ends of said tie rods extending through the bearings in which the posts are mounted and through the mud sill, said rods having nuts threaded upon their upper and 10 lower ends to clamp the posts between the bearing caps and the lower bearings arranged on the sill, and a horizontal bolt

connecting said hollow metal posts and extending through the same and between said vertical tie rods, substantially as and for 15 the purpose set forth.

In testimony whereof we hereunto affix our signatures in the presence of two witnesses.

TRUMAN McCORD.

WILLIAM C. BIGLER.
